VIBRATING SCREEN

Homer B. Slater, Dormont, Pa., assignor to The
Koppers Company of Delaware, a corporation
of Delaware

Application February 15, 1930, Serial No. 428,579

6 Claims. (Cl. 209—348)

This invention relates to vibrating screens and in particular to apparatus for subjecting the screen to vibrations of high frequency and low amplitude.

5 One type of vibrating screen, as previously built, comprises a vibrating element attached directly to a portion of the screen instead of to the supporting frame of the screen. The vibration of the screen produced a flexing or "whip-
10 ping" of the same. Moreover, the amplitude of vibration was not uniform throughout the area of the screen.

In other types of vibrating screens, the entire weight of the screen and its supporting frame 15 were suspended from the vibrator and the driving motor or other source of power was subjected to the full effects of the vibration.

An object of the present invention is to cause all parts of the screen to vibrate at a substantially uniform amplitude without the use of a special driving motor and without supporting the weight of the screen on the vibrating means.

Further objects are to make it possible to adjust the degree of vibration from zero to maximum while the screen is in operation and to have an important component of the vibration at right angles to the direction of travel of the material being screened.

In the screen of my invention, the entire weight 30 of the screen cloth, its supporting frame and the material resting thereon is supported on a pivot that is independent of the vibrating means.

The screen is caused to oscillate transversely to the path of travel of the material whereby 35 the maximum action of the screen is obtained as, in effect, the path of travel on the screen is lengthened.

In the drawing:

Figure 1 is a vertical section on line I—I of 40 Fig. 2;

Fig. 2 is a side elevational view partly in cross-section of the vibrating screen, parts being broken away; and

Fig. 3 is a vertical sectional view of a portion 45 of the vibrating mechanism, parts being broken away.

The vibrating screen of my invention comprises screen cloth 1 that is held at its side edges by a frame 2 pivotally supported by a pin 3. The latter is supported by a rectangular hanger or extension 4 projecting downwardly from a supporting bracket 5.

The vibrating means comprises a motor 6 supported by the bracket 5 and having a shaft 7 extending through bearings 8 in the hanger 4.

The shaft 7 is provided with an eccentric portion 9 surrounded by a ring 10 with roller bearing 11 therebetween.

Springs 12 extend between opposite sides of the ring 10 and vertical arms 13 integral with the frame 2. Each arm 13 is provided with a tubular recess for the outer end of the corresponding spring 12 and the compression of the springs may be adjusted by means of screw-threaded shafts 14 having hand-wheels 15. The inner ends of the shafts 14 have suitable blocks for engaging the outer ends of the springs.

The amplitude of vibration of the screen frame about the pivot pin 3 is limited by stop members 16 which extend outside each arm 13.

The screen cloth 1 is secured to side plates 17 of the frame 2 that are pivotally mounted on the outer ends of the main body portion of the frame 2 and retained thereon by means of outer circular screw-threaded clamps 18. The clamps 18, when loosened, permit adjustment of the inclination of the screen cloth 1 and side plates 17 with the horizontal. An adjustable chain 19 and the clamps 18 hold the screen at the desired angle.

Adjustable spacers 20 may be placed on either side of the clamps 18, thereby regulating the distance between the two side plates 17 and the tension in the wire screen 1. In Fig. 1, the spacers 20 are shown outside the clamps 18, the side plates 17 being relatively close to each other.

In operation, it is only necessary to adjust the compression of the springs 12 by means of the hand wheels 15 in order to regulate the amplitude and intensity of the vibrations. Such adjustments may readily be made while the screen is in operation.

Advantages of my invention are that an ordinary driving motor is used and the vibrating element is composed of few and simple parts. The weight of the screen, the material resting thereon and the supporting framework for the screen is not carried by the vibrating element but by the pivot pin.

All parts of the screen are vibrated through approximately the same amplitude and the direction of the vibration is substantially at right angles to the direction of flow of material down the screen. There are no vibrating areas alternating with quiet nodes as is the case where a vibrator is directly connected to an otherwise unsupported portion of the screen.

The vibration of the screen occurs in arcs of circles having pivot pin 3 as their center, as shown by arrows 21 in the drawing. The move- 110

ments through these arcs deviate just sufficiently from straight horizontal motions to provide a maximum separating effect on material being screened.

5 I claim as my invention:

1. Separating apparatus comprising a support, a screen frame pivotally mounted thereon, a shaft mounted on said support, an eccentric mounted on said shaft, arms on said frame extending on opposite sides of said eccentric, and compression springs between said arms and said eccentric.

10 2. In a vibrating apparatus, the combination of a stationary pivotal support, a screen frame suspended from and pivotally mounted on said support, means for adjusting the angle of said frame relative to the horizontal, means for oscillating said frame on its support, said oscillating means comprising an eccentric member engaging a portion of said frame above and in vertical alignment with said pivotal support, and independently adjustable spring members one disposed on each side of said oscillating means and between the same and said frame for varying 25 the degree and intensity of oscillatory movement imparted to said frame by said oscillating means.

3. In a vibrating screen apparatus, the combination of a stationary support having a horizontal axis, a screen frame depending from and centrally mounted for oscillatory movement on said axis, said frame having an upstanding portion, means for adjusting the inclination of said frame relative to the horizontal, a rotatable vibrating shaft journaled in said support above the axis of said frame, eccentric means on said shaft cooperating with the upstanding portion of the frame to oscillate the latter on its axis transversely of its longitudinal extent, and adjustable spring means disposed between said eccentric means and said frame for varying the amount of oscillatory movement imparted to said screen frame by said vibrating shaft while the apparatus is in operation.

45

4. In a vibrating screen apparatus, the combination of a stationary support having a horizontal pivotal axis, a screen frame depending from and centrally mounted for oscillatory movement on said axis, said frame having upstanding portions, a rotatable vibrating shaft journaled in said support above and parallel to the pivotal axis of said frame, an eccentric on said shaft, and resilient means disposed between and engaging said eccentric and the upstanding portions of said frame, whereby the rotation of said eccentric imparts an oscillatory movement to said frame on its axis.

5. In a high frequency vibrating and separating apparatus, the combination of a stationary support having a horizontal stub shaft, a screen frame mounted about its longitudinal axis on said shaft in balanced relation thereto, said frame having spaced upstanding portions one on each side of said stub shaft, and an eccentric shaft disposed in vertical alignment with and parallel to said stub shaft between said upstanding portions and connected to the latter for imparting high frequency oscillations to said frame on said stub shaft.

6. In a high frequency vibrating and separating apparatus, in combination: a stationary support having a pivot, a screen frame mounted on said pivot, a rotatable shaft having an eccentric portion for vibrating said frame on said pivot, a pair of spring members one on each side of said eccentric portion and between the eccentric portion and the frame for imparting high frequency vibrations from said shaft to said frame, and means mounted on said frame and engaging said springs for adjusting the tension of the latter, to vary the degree of vibration of said frame from zero to maximum independently of the rotation of said shaft and while the apparatus is in operation.
